UNITED STATES PATENT OFFICE

129,968

DESIGN FOR A BOTTLE OR SIMILAR CONTAINER

Grace Chess Robinson, New York, N. Y., assignor to Mary Chess, Inc., New York, N. Y., a corporation of New York

Application June 17, 1941, Serial No. 101,493

Term of patent 14 years

To all whom it may concern:

Be it known that I, Grace Chess Robinson, a citizen of the United States, residing in the Borough of Manhattan, county, city, and State of New York, have invented a new, original, and ornamental Design for a Bottle or Similar Container, of which the following is a specification, reference being had to the accompanying drawing, forming a part thereof.

Fig. 1 is a top plan view of the bottle or similar container embodying my new design.

Fig. 2 is a side elevational view thereof.

I claim:

The ornamental design for a bottle or similar container, as shown.

GRACE CHESS ROBINSON.
